(57) **CLAIM**

The ornamental design for a reusable hot and cold therapy wrap, as shown and described.

DESCRIPTION

FIG. 1 is an overhead, frontal perspective view of a reusable hot and cold therapy wrap, in an open position, showing my new design;

FIG. 2 is a top view thereof;

FIG. 3 is bottom view thereof;

FIG. 4 is an overhead, frontal perspective view thereof, with a body portion of the wrap being in an expanded position and having an optional gel pack in a sleeve or a pocket thereof;

FIG. 5 is an angled, overhead perspective view thereof and with the optional gel pack extended from said pocket;

FIG. 6 is an angled, overhead perspective view thereof, in a closed position;

FIG. 7 is a side view thereof in the closed position;

FIG. 8 is a detailed, inside view of the body portion thereof in the expanded position;

FIG. 9 is an underside view of a strap of the reusable hot and cold therapy wrap;

FIG. 10 is a top side view of the strap of FIG. 9;

FIG. 11 is a first angled side perspective view of the reusable hot and cold therapy wrap in the closed position and configured for use; and,

FIG. 12 is a second angled side perspective view thereof in the closed position.

In the drawings, the broken lines depicting portions of the reusable hot and cold therapy wrap form no part of the claimed design; all other broken lines depict unclaimed environmental subject matter and form no part of the claimed design. Stitching throughout the Figures is in dot-dot broken lines and forms no part of the claimed design.
